JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed September 8, 1925. Serial No. 54,930.

My invention relates to circuit breakers, and it has particular relation to alternating-current circuit breakers.

An object of my invention is to provide an alternating-current air circuit breaker which will interrupt large currents at high voltages without arc re-ignition and with minimum line disturbance.

In oil circuit breakers which have heretofore been almost exclusively utilized for interrupting high-power circuits, the current interruption is effected by drawing an arc under oil, in order to prevent arc re-ignition after the alternating current in the arc has passed through zero value.

Very serious disadvantages are presented by oil circuit breakers, which have been the only means heretofore found suitable for interrupting the circuits of modern alternating-current distribution systems, capable of energy concentrations of the order of a million kva. The arc energy of a heavy short-circuit, released under the oil when opening the arcing contacts of the circuit breaker, decomposes the oil and generates gases with explosive violence. To withstand the tremendous pressures developed by the generated gases, oil circuit breakers must be enclosed in enormous oil tanks of massive construction.

As a result of the difficulties just outlined, the design of circuit breakers for power installations has become of more concern than the design of the generating equipment that supplies the current and the cost of the interrupting equipment frequently approaches that of the generating equipment.

Another great disadvantage of oil circuit breakers is the fire hazard and danger to life involved in their operation. The gases developed in such circuit breakers form explosive mixtures, and, in many cases, the high-pressure tanks are burst by the resulting explosions, causing oil fires and endangering the surrounding property and the lives of the personnel.

I have found that the arc resulting from the opening of a circuit breaker in air can be fully interrupted and that arc re-ignition may be prevented even to a larger extent than

in the case of oil circuit breakers, by introducing, into the space between the arc electrodes special de-ionizing means in the form of conducting sheets or nuclei placed across the arc which rapidly reduce the conductivity of the arc space after the arc current passes through zero. The de-ionizing means are preferably so arranged as to interfere as little as possible with the arc play as long as the arc lasts. By providing a sufficient number of such de-ionizing sheets, I am able to fully control the speed at which the space between the arc electrodes loses its conducting character and becomes an insulator without introducing special arc-quenching mediums, such as oil or similar substances.

My invention will best be understood by reference to the accompanying drawings, wherein

Figure 1 is a side elevational view of a circuit breaker embodying my invention, a part of the arc chamber being shown in section;

Fig. 2 is a sectional view on the line II-II of Fig. 1, showing the arc chamber of the circuit breaker;

Fig. 3 is a top plan view of the arc chamber and the arc blow-out magnet of the circuit breaker shown in Fig. 1;

Fig. 30 is a vertical sectional view including all of the modifications of my invention.

Referring to Figs. 1 to 3, inclusive, a circuit breaker is shown comprising two main contact members 1 and 2 mounted upon insulating bushings 3 and 4 secured, one above the other, upon a structural-iron supporting frame 5. The contact members 1 and 2 comprise terminal rods 6 and 7 extending to the back side of the supporting frame, through perforations in the centers of the insulating bushings 3 and 4.

Supported jointly by the lower insulating bushing 4 and an insulator 11, below the same, is the main bracket 12 of the circuit breaker, carrying a shaft or point 13 upon which are rotatably mounted a main contact arm 14 and an upwardly extending arcing-contact arm 15. The main contact arm holds a main contact brush 17, consisting of laminated copper punchings, against the main contact members 1, 2.

The upwardly extending arcing-contact arm 15 of the circuit breaker carries an arcuate movable contact shoe 19, engaging a stationary arcing contact member 20, for effecting the final interruption of the circuit.

The stationary arcing contact member has a slight tilting motion, being pressed downwardly, against the contact shoe 19, by means of a spring 21. The stationary member 20 is connected, by means of a flexible conductor 22, to one terminal 23 of blow-out coils 24, the other terminal 25 of the coil being electrically connected to a metallic supporting frame 26 which is in electrical engagement with the upper main contact member 1.

The movable arcing contact shoe 19 is electrically connected to the swinging arm 15, which is, in turn, connected to the lower main contact member 2 through a flexible shunt 27 adjacent to the pivot 13.

The switch arms 14 and 15 are operated by a toggle mechanism comprising a bell-crank lever 28 which is pivoted to the switch frame 12 at 29. The inner end of the bell-crank lever is pivoted to two links 30 and 31 which are connected to the two switch arms 14 and

15, respectively. The switch arm 15 is drawn towards its open position by a spring 32, and the toggle link 31, which is connected thereto, is disposed above the line of centers of the toggle, so as to lock the switch in closed position. The circuit breaker is tripped by moving the outer end of the bell-crank lever 28 upwardly, thus breaking the toggle.

When the switch is opened, the movable arcing shoe 19, being of arcuate shape, does not break contact with the stationary contact member 20 until after the main contact members 1 and 2 are disengaged by the main contact brush 17. A pair of auxiliary contact members 33 and 34 are usually also provided to relieve the main contact members of the arcing incident to the transfer of the current from the main contact members to the inductive shunt circuit comprising the final current interrupting contact members 19 and 20 and the blow-out coil 24. As shown in Fig. 1, the stationary auxiliary contact member 33 is mounted on the frame 26 which is in electrical contact with the upper main contact member 1, and the movable auxiliary contact member 34 is mounted on the top of the main contact brush 17, which is in electrical contact with the lower main contact member 2, through the switch arm 14. The movable auxiliary contact member 34 is pivoted at 35 and is pressed toward the stationary contact member by means of a spring 36, in order to secure a rolling and wiping motion when engaging or disengaging the stationary auxiliary contact member 33.

The principal feature of my invention resides in the provision of new and improved means for extinguishing the arc drawn between the arcing contact members 19 and 20. To this end, an arc chute 40 is provided above the arcing contact members 19 and 20. The lower portion of the chute terminates in two horn-like arcing plates 41 and 42, the plate 41 being in electrical engagement with the stationary arcing contact member 20, and the plate 42 being provided with resilient fingers 43 which engage the movable arcing contact shoe 19 when the latter is in its final open position, so that the arc is transferred from the arcing contact members 19 and 20 to the horn-like plates 41 and 42 leading to the arc chute 40.

The arcing chute 40 consists of four spaced vertical conducting plates 44, 45, 46 and 47, dividing the space between the upper ends of the horn-like arcing plates 41 and 42 into three separate serially-connected arcing chambers 48, 49 and 50, the two end plates 44 and 47 being in electrical contact with the arcing plates 41 and 42, respectively. Each arcing member is sub-divided into a large number of small spaces by means of conducting sheets or grids 51, disposed parallel to the arcing terminal plates 44 to 47, inclu-

sive. The conducting sheets 51 are preferably reticulated, as will be explained later. In the embodiment shown in Fig. 1, they are wire grids 51 of brass.

5 The space between the horn-like arcing plates 41 and 42 may be enclosed, at the sides, by large insulating shields 52 engaging the edges of the plates. In like manner, the arcing chute 40 may be enclosed by insulating plates 53 engaging the edges of the plates 44 to 47.

10 The arc is forced into the arcing chambers 48, 49 and 50 of the chute, by means of the aforementioned blow-out coils 24, which are shown as being provided with a horseshoe-shaped laminated iron core 54 terminating in pole-shoe plates 55 and 56, the plates 56 being the larger, and being disposed in engagement with the insulating walls 52 and 53, as shown in Fig. 2. The function of the blow-out coil 24 is to cause the arc stream to be displaced laterally into the space traversed by the grid sheets 51, within an interval of time which is short as compared to the half-period 15 of the alternating-current circuit to which the breaker is connected, so that the arc stream is playing through or between the grid sheets when the current first passes 20 through zero value after the striking of the 25 arc.

30 The grid sheets 51 extend across the entire width of the arcing chambers, between the insulating walls 53, and are insulated from each other by insulating strips 57, of mica or other heat-resistant material, as best 35 shown in Fig. 2, leaving a substantially unobstructed air path between the opposing arc electrode plates in the middle of each 40 chamber.

45 The perforated grid sheets 51 are preferably so made as to permit a continuous arc between the arcing electrodes and to interfere as little as possible with the arc play. However, when the arc current passes through zero value at the beginning of the next alternation, the grids filling the space between the arcing electrodes exercise an enormous de-ionizing action, as hereafter described, rapidly 50 restoring the air space in one or more of the arcing chambers to its original insulating condition and preventing the re-striking of the arc upon the rise of terminal voltage which follows the extinction of the arc in 55 such chambers.

55 The grid chamber or arc chute 40 is of sufficient extent, as compared to the speed of arc motion therewithin, to insure that the final interruption of the arc shall be accomplished within the chute. The arc movement within the chute is made fast enough to prevent melting of the grids or destruction of the insulation near the arc under ordinary conditions of discharge.

60 65 In order to understand the de-ionizing

action of the grids utilized in the arcing or de-ionizing chambers of my improved circuit breaker, it will be helpful to briefly discuss the phenomena taking place in an alternating-current arc discharge.

70 *Spark discharge.*—Under ordinary conditions, air and other gases are excellent insulators. However, when a sufficiently high potential is applied to two electrodes spaced by an air gap, the air suddenly changes from its normally insulating state to a conducting state. This change, known as a spark discharge, is explained as follows: Air normally has a minute degree of ionization due to the 75 radiation of radio-active elements in the earth. Under the influence of small electric potential gradients, this ionization provides a slight conductivity which is detected only by the most sensitive instruments. Under the influence of large electric potential gradients, these few ions move very rapidly, and their collisions with neutral molecules may be so energetic that they may actually disrupt some of them into positively and negatively charged parts. Thus, new ions and electrons 80 are formed.

85 For example, assume that there is a single free electron between two electrodes to which a voltage in excess of breakdown voltage is applied. This electron moves rapidly toward the anode, and of its large number of 90 collisions with neutral molecules, assume that 1000 are sufficiently energetic to produce disruption. We then have 1000 new positive ions and 1000 new negative ions. The 100 positive ions start moving toward the cathode. Positive ions, having a much greater mass, are much less effective than electrons in 95 producing ionization-by-collision. Assume, further, that these positive ions, in moving to the cathode produce only two new electrons near the cathode. These two electrons moving to the anode will produce 2000 new pairs of ions. The 2000 positive ions moving to the cathode will produce 4 new electrons; 100 these four electrons will produce 4000 positive ions, and so on until great conductivity 105 will be produced.

110 The number of pairs of positive and negative ions produced by collision by an electron per centimeter of advance in the direction of the electric field, and the corresponding quantity for a positive ion, are rapidly increasing 115 functions of the electric gradient.

120 *Glow discharge.*—As soon as a discharge has been initiated by the process of ionization-by-collision, as just described, the electric field in the gap becomes distorted. A steep voltage gradient is developed in a thin layer, known as the cathode dark space, adjacent to the cathode. The voltage drop in said thin layer, or the cathode drop, is of the order of 300 volts for ordinary electrode materials in air.

125 130 If the electrodes are cold when the gap is

broken down and the current density is not too high, the conduction across the gap takes the form of a glow discharge, in which the positive ions, and to a smaller extent the electrons and negative ions, moving through the high-gradient field of the cathode drop toward the cathode and the anode, respectively, continue to produce new electrons and ions by collision with the air molecules in the thin layers wherein the cathode drop occurs, thus supplying sufficient electrons and ions to produce a highly conducting state, or low voltage gradient, in the remainder of the gap.

Arc discharge.—If, at some spot next the cathode, the energy input is sufficient to raise its temperature to such degree that it begins to emit electrons thermionically, or to heat a layer of gas very close to this spot to such a temperature that it is thermally ionized, the current will concentrate at such spot. The cathode drop then becomes much smaller than in the glow discharge, since the necessary conduction is produced by thermionic electron emission, or by thermal ionization of gas very close to the cathode, rather than by ionization-by-collision. It is necessary, however, that the voltage drop in said thin cathode layer be sufficiently high, in order that the available energy input may maintain the cathode or adjacent gas at a temperature producing the required thermionic emission or thermal ionization. It is, in general, also necessary that the voltage drop in said thin cathode layer be sufficiently high to produce therein electrons by ionization for neutralizing the space charge of the electrons. For ordinary electrode materials, twenty volts is sufficient for the purposes just mentioned.

In addition to the voltage drop at the cathode, there is a voltage drop of about ten volts near the anode of the arc. Positive ions are produced in the field of the last-mentioned drop, by collisions of the swiftly moving electrons coming from the cathode. High temperature at the anode is not essential for the maintenance of the arc.

The voltage gradient in the main body of the arc stream, between the regions immediately adjacent to the cathode and the anode, is very low. It is usually not sufficient to produce any material ionization-by-collision. The positive ions necessary to neutralize the space charge of the electrons in the main body of the arc stream are probably the result of thermal ionization of the gas.

Thus, in an arc, most of the current is carried by the rapidly moving electrons which move from the cathode and stream toward the anode. The space between the cathode and the anode is filled with positive ions neutralizing the space charge of the electrons and rendering the arc highly conductive. The positive ions are produced by collision in the spaces near the cathode and the anode,

and in the remainder of the arc stream by thermal ionization.

Alternating-current arc.—In an alternating-current arc, the arc current passes periodically through zero. The electrode which was a cathode in the previous alternation becomes an anode; the anode of the previous alternation becomes a cathode for the next following alternation.

At the exact moment when the current becomes zero, the space between the electrodes is still highly ionized. The voltage gradient is nearly zero throughout the arc space, so that there is no ionization-by-collision. The electrode which is beginning to become a cathode is at a temperature too low to emit electrons thermionically. Thermal generation of ions in the gas is being reduced rapidly by the cooling of the gas. Very shortly after the current is zero, generation of new ions has practically ceased.

At the same time, the space between the electrodes is rapidly becoming de-ionized. A certain proportion of the electrons will come sufficiently close to positive ions to recombine with the same, thus neutralizing their charges. The rate of recombination is proportional to the density of the positive and negative ions in the space. If there is no fresh supply of ions, recombination will reduce the density of ionization inversely with the time. Thus, the space is losing its conductivity, and if the formation of new ions can be prevented, the arc will not re-ignite.

Referring to Fig. 5, the + and - signs represent the ions in an arc discharge in air, between an electrode 79, which is becoming a cathode, and an electrode 80, which is becoming an anode, at the moment when the voltage and current are zero. Recombination is taking place, so that in Fig. 6, which represents the conditions a short time later, the density of ionization is reduced. During the time between the conditions illustrated in Figs. 5 and 6, the voltage has been rising, producing a gradient which moves electrons away from the cathode 79 and which moves positive ions toward the cathode 79.

There is thus formed a region 81 next to the cathode, which is nearly denuded of ions, only a few slowly moving positive ions being in said region, on their way to the cathode. The space 81 adjacent to the cathode thus has a much higher resistivity than the rest of the space and, consequently, most of the voltage applied to the electrodes will appear across said cathode space, producing an electric field of high gradient therein. As time goes on, the electrons will be repelled further from the cathode, and the high-resistance region will grow in thickness.

A similar de-ionized sheath 82 will also appear next to the anode. Owing to the relatively high mobility of the electrons, the gradient in this sheath will be very much 130

less than that at the cathode, and it will not be further considered.

Thus, as a result of the action of the electric field, two regions of different characteristics are produced. In the region 82 adjacent to the anodes, the electric gradient is very low, and the loss of ions is occurring principally by the process of recombination, in the manner previously described. The region 81 adjacent to the cathode is almost completely de-ionized by reason of the repulsion between the cathode and the electrons. The boundary between the region 81 and the ionized arc spaces continues to move outwardly from the cathode as the de-ionization proceeds.

While the de-ionized region or sheath 81 near the cathode is thus growing in thickness, the applied voltage is also increasing. 20 If the rate of voltage rise is so high that it imparts to the high-resistance sheath a voltage gradient sufficient to move the relatively few positive ions remaining in said sheath at a velocity at which they will produce thermal ionization or ionization-by-collision, this region will lose its high resistance.

The voltage which otherwise would be consumed by the cathode sheath is then transferred to the still highly ionized, highly conducting body of gas, a heavy current starts and the arc re-strikes.

However, if the de-ionization proceeds so fast that the thickness of the de-ionized cathode sheath increases at such rate that the voltage gradient in this region never reaches a value at which ionization-by-collision occurs, and the energy input is not sufficient to produce thermal ionization, the entire space between the electrodes gradually becomes insulating and the arc does not re-ignite. The circuit is accordingly interrupted. Thus, if the rate at which the voltage rises be maintained sufficiently low compared to the rate of de-ionization, the voltage gradient in the cathode sheath will be too low for ionization; no new ions will be generated; only de-ionization will take place; the ions will be swept out of the arc path as the cathode sheath grows; and the arc will be permanently extinguished.

Application to circuit breakers.—Based upon the analysis of the phenomena taking place upon the opening of the arcing contacts of an alternating-current circuit breaker, in the manner described hereinabove, I have determined the permissible rate of voltage rise at which no arc-re-ignition would take place between such contacts as are ordinarily used. I have found that, with ordinary prior-art circuit breakers, operating in air, the permissible rate of voltage is so low that it is not feasible to make commercial, large-current breakers for any voltages above relatively low values, on account of the physical limitations imposed by the material of

the contacts, the possible separation of the electrodes, and the constants of the circuit to be opened. Thus, for a pair of copper electrodes separated one inch, the rate of de-ionization is such that the rate of rise of voltage must be limited to less than 1×10^6 volts per second, if re-ignition is to be prevented.

If the alternating current to be interrupted is in phase with the voltage, i. e., of unity power factor, the rate of voltage rise is that of the alternating voltage wave, i. e., in commercial circuit breakers, that of a 60-cycle wave. However, the ordinary circuits and conditions under which practical circuit breakers must operate require the opening of currents having a power factor considerably different from unity. In such case, the maximum rate of voltage rise across the terminals of the circuit breakers is principally dependent upon the constants of the circuit. Thus, in an inductive circuit the voltage rise across the open terminals is almost instantaneous.

The voltage rise under such conditions may, however, be reduced to lower values by shunting a suitable resistor in parallel to the open contact terminals. To limit the rate of voltage rise to less than 1×10^6 volts per second, in the case of a contact separation of one inch, considered above, and an ordinary power circuit of a 2200 volt, 60 cycle line, it would require shunting resistors of considerable size and cost, which would be required to carry a very large part of the interrupted current. Such constructions would be out of the question for commercial circuit breakers.

One of the principal features of my invention is an artificial increase of the rate of de-ionization of the space of the arc resulting upon opening a circuit breaker, immediately after the passage of the arc current through zero. More particularly, I introduce into the arc space a large number of what may be termed "artificial" cathodes, multiplying the de-ionizing action of the main cathode and thus reducing the time of de-ionization to a fraction of the value it would otherwise require.

The shunting resistors, if they are used at all, are so proportioned with respect to the greatly increased permissible rate of voltage rise as to positively avoid a voltage gradient at which ionization-by-collision will occur.

In the circuit breaker shown in Figs. 1 to 4, the artificial cathodes are made in the form of wire grids 51 disposed across the arc path and assembled into a unitary structure. As the arcing contact arm 15 opens and draws the arc, the same is blown upwardly into the grids by the field of the arc-blow magnets. The arc is split into three arcing sections, in series with each other, for reasons to be explained hereinafter. In each section, an arc extends between the opposite arc terminal plates 44 to 47, respectively, playing freely through the perforations in the grids.

- The ions which discharge to the grid wires are probably only few in number in comparison to the number of ions constituting the arc stream. But, at the moment when the arc current is passing through zero, ionization-by-collision has ceased, and the gas is becoming too cool for thermal ionization; recombination is taking place, reducing the density of the ions; and at that moment, the discharging 10 of ions to the grid wires radically reduces the conductivity of the space around the grids. Metallic parts of the grids thus, to a certain extent, act like cathodes forming centers of de-ionization, as will now be explained.
- 15 In Fig. 7, grid wires 51 are shown disposed in the space between the electrodes 44 and 45 of Fig. 1, at a moment which is soon after the former has become a cathode and the latter an anode, as in the case of Fig. 6.
- 20 At a slightly earlier moment, when the current was passing through zero value, the space around the grids had been highly ionized throughout, filled with electrons and positive ions, as indicated in Fig. 5.
- 25 At the moment chosen for Fig. 7, the lines of force of the increasing electric field, entering the grid wires on one side and leaving the same at the other side, are causing the sides of the wires facing the cathode to act as anodes and the sides facing the anode to act as cathodes. A sheath 83 is formed on the cathode side of each wire, similar to the sheath 81 in Fig. 6. Under the influence of the increasing voltage, the sheaths 83 around all of the 30 wires grow, taking the shape shown in Fig. 7, until the individual sheaths merge into a single sheath 84 over the entire surface of a grid 51, as shown in Fig. 8, similar, in every respect, to the sheath 81 near the cathode.
- 35 In the manner just described, the de-ionization proceeds rapidly from a large number of sheaths or deionizing kernels 84, acting like so many cathode sheaths. The rising voltage is now distributed over a large number of high-40 resistance, de-ionized regions, thus reducing the voltage gradient sufficiently to prevent ionization-by-collision in the gap space between the electrodes.
- The rate at which the openings in the grids 45 are de-ionized, so that the entire grid begins to act like a single de-ionizing surface similar to the cathode, depends upon the size of the openings. I have found that, if the openings in the grids are sufficiently small, the rate of 50 rise of voltage may be as high as 5×10^6 volts per second per grid, without danger of ionization and arc re-ignition.
- 55 Thus, by interposing nine grids, of the character mentioned above, across the arc path in the space between electrodes spaced one inch apart, as in the case considered before, the permissible rate of voltage rise will be increased from less than 1×10^6 to 50×10^6 volts per second. With the 2200 volt, 60 cycle circuit considered above, the shunting resis-

tors would have to carry only a little more than 2% of the interrupted current in order to prevent re-ignition. By properly selecting the number of de-ionizing grids, the rate of de-ionization may be controlled very accurately, and practical air circuit breakers may be constructed to operate under conditions which were heretofore believed to be entirely beyond the possible operating range of such apparatus.

Operation of the circuit breaker.—If the circuit breaker operated in a resistance-less circuit, consisting of a source of alternating current and an inductance connected in series, and if the circuit were interrupted when the current was zero, the voltage at the interrupting terminals would instantaneously rise to the peak voltage of the source. That is, the rate of rise of voltage would be infinite.

However, in any practical circuit, on account of the inherent capacity and leakage, the rise of voltage is not instantaneous, but it is usually very rapid. When my improved breaker is utilized in any practical circuit carrying a sufficiently small current, the rate of rise of voltage, as limited by the circuit, will be less than that necessary to re-ignite the arc which is de-ionized by means of a grid structure, as described above. However, if the currents are very large, the rate of voltage rise, as limited by the circuit, may be greater than that required for preventing restriking of the arc, as explained hereinbefore.

In order to secure reliable opening of the circuit breaker, independently of the magnitude of the current to be broken, and independently of the constants of the circuit, the improved circuit breaker shown in Figs. 1 and 4 is arranged to first reduce the current to be opened to a fraction of its maximum short-circuit value, before finally interrupting the circuit. To this end, the arc drawn by the arcing contact of the circuit breaker is split into three sections, as explained above, each arc playing in a separate chamber; the first arcing chamber 48 being shunted by a resistor 85, as shown in the circuit diagram in Fig. 4, the second arcing chamber 49 being shunted by a much higher resistance 86, and the last arcing chamber 50 being without shunt.

In operation, when the arcing contact arm 15 is opened, the arc which is drawn between the contact members 19, 20 is blown into the three chambers of the arc chute 40 of the circuit breaker, the three arc sections being in series. The electrical conditions in the circuit are shown in Fig. 9, wherein the sine-wave curve 87 represents the generator voltage plotted against time, the heavy dotted curve 88 represents the line current, the light dotted curve 89 represents the voltage across the terminals of the first arcing chamber 48, and the dot-and-dash curve 90 represents the voltage across the terminals of the two re-

maining arcing chambers 49 and 50 in series. The conditions illustrated in Fig. 9 correspond to those existing in an inductive circuit which imposes the heaviest duty on the interrupting capacity of the circuit breaker. The current is shown as being displaced from the voltage wave by almost 90°. As the current passes through zero value at 91, the voltage across the terminals of the circuit breaker rises almost instantaneously to nearly the full value of the generator voltage and would cause re-ignition in all three sections of the arcing chamber but for the fact that the rise of voltage causes a flow of current through the relatively low value resistor 85, Fig. 4, shunting the first section 48 of the arcing chamber. The rate of voltage rise across the terminals of this section of the arcing chamber is thus slowed down, as shown by the steep portion 89', of the light dotted curve 89.

With heavy currents, the rates of voltage rise in the high-resistance shunt 86 of the second section 49 of the arcing chamber 40, and in the unshunted section 50 of the arcing chamber, will be so high that the arc may re-ignite in these sections during the next following half-cycle, as indicated by the last half-cycle of the current curve 88 in Fig. 9. However, the phase of the current with respect to the voltage will be greatly changed on account of the resistor 85, which is now in series with the circuit, so that the current which now constitutes the arc in the two arcing chambers 49 and 50 will be almost in phase with the voltage and will go through zero when the voltage is zero. At the same time, the resistor 85 will reduce the current through the circuit breaker to a fraction of its original value. At the next reversal of the current, when the current goes through zero, the rate of voltage rise will be practically that of a 60-cycle wave and will not be sufficient to cause restriking of the arc in the second and third sections of the arcing chamber.

When interrupting heavy currents, as in the case considered above, the first section 48 of the arcing chute or de-ionizing chamber 40 is usually sufficient to reduce the interrupted current to a fraction of its original value and to improve the power factor of the same so that the unshunted section 50 of the circuit breaker is sufficient then, to fully open the circuit. In such cases, the second section of the circuit breaker is not called upon to perform any duty.

However, when the interrupted current is small and of low power-factor, such as the magnetizing current of transformers connected to the line, the resistance 85 shunting the first section 48 of the de-ionizing chamber is usually so low as compared to the reactance of the circuit that it is practically without influence upon the magnitude and power factor of the line current; in this case, how-

ever, the second section 49 of the de-ionizing chamber opens together with the first section 48 at the first current zero. The relatively high-value resistor 86 shunting the second section of the circuit breaker is sufficient to materially reduce the small magnetizing current and to improve its power-factor so that the unshunted section 50 of the circuit breaker is capable of interrupting the residual current before the next alternation.

Thus, in case of relatively heavy, low power-factor currents, the first section of the de-ionizing chamber opens at the first current zero, the second and third sections opening together at the second current zero. In case of relatively small, low power-factor currents, the first and second sections both open at the first current alternation, while the third, unshunted, section opens at the second alternation. High-power factor currents, of any magnitude, are usually opened by all three sections at the first current zero.

In a typical circuit breaker designed for 8600 volts, as shown in Fig. 1, I employ three de-ionizing sections 48, 49 and 50, each section being 4" between arc terminals, with 16 grids per inch. The grids 51 are of brass gauze having wires $\frac{3}{16}$ " thick and perforations $\frac{3}{16}$ " wide. The circuit breaker is designed to open currents of the order of 20,000 amperes. The resistor 85 shunting the first section of the de-ionizing structure used in this circuit breaker is 8 ohms and the resistor 86 shunting the second section of the circuit breaker is 160 ohms. The arc chute is 24 inches high, and the speed of arc motion is approximately 100 ft. per second.

Fig. 10 shows a modification of my invention wherein the three arcing sections of the circuit breaker are combined into separate units, 91, 92, 93 each section having its own arcing terminals 94, 95 and 96 and separate auxiliary arc-transfer terminals 97, 98 and 99, with separate blow-out coils 100, 101 and 102 connected in series with the several arcing units. The first arcing section 91 is shunted by an impedance in the form of a condenser 103, reducing the arcing current to a fraction of its value; the second section 92 is shunted by a condenser 104 having a much higher impedance for still further decreasing the arcing current; and the last section 93 is without shunt. The blow-out coils 100 to 102, cooperating with the individual arcing sections, have a gradually increasing number of turns in order to give the requisite arc blowing action, notwithstanding the reduced arcing currents in the sections.

The mechanical separation of the several auxiliary, or arc-transfer, contacts of the circuit breaker of Fig. 10 is preferably so timed that the openings of the arc-transfer contacts 97, 98 and 99, respectively, follow each other at intervals of one-half cycle or more, so that the arc is first interrupted only

in the first section 91, reducing the line current through the series impedance 103. The section 92 then opens, further reducing the residual current by means of the impedance 104. The last section 93 finally opens to completely interrupt the circuit. Instead of the condenser shunts 103, 104 shown in Fig. 10, I may use a resistor shunt, such as shown in Fig. 4, or a more complex shunt network.

Design of the de-ionizing structure.—Several features must be observed in the design of the de-ionizing structure utilized in my improved circuit breaker. First of all, it is considered desirable to make the grids with sufficiently large interstices to permit the arc to play therethrough, as if there were no obstruction in the space between the opposing electrode surfaces of the arc. It is desirable that the arc should play freely through the grid openings, without splitting up into many small serially connected independent arcs, with their many separate cathode and anode terminals on different portions of the grids. With the arc velocities obtainable in a chute of moderate length and with currents of 10,000 amperes or more, there would, otherwise, be formed hot cathode spots on the grids, melting the metal of the grids, and the heated vapor slowing down the rate of de-ionization.

On the other hand, it is desirable to make the openings in the grids as small as possible, in order to increase the rate of de-ionization which is the greater, the more uniform the metal of the de-ionizing sheets is distributed across the arc space. Thus, the practical design of the grids is a compromise between the requirement for large openings in the path of the arc, in order to prevent the splitting of the arc into many small arcs, and the requirement for small grid openings in order to secure a large rate of rise of re-ignition voltage.

I have found that the limiting rate of rise of voltage which may be applied without arc re-ignition is a function of the size of the grid openings, the thickness of the grid, the spacing between the grids and the number of grids. In general, the limiting rate of rise of voltage per grid is increased by decreasing the grid spacing, decreasing the size of the grid openings, and increasing the thickness of the grids.

For example, with grids of brass gauze, woven of wires .032 inches diameter and .03 inches between wires, the limiting rate of rise of voltage was found to be 3.3×10^6 volts per second per grid when the grids were spaced .083 inches apart, and 5.1×10^6 volts per second per grid when they were spaced .030 inches apart, thus showing the advantage of close grid spacing.

Again, with grids consisting of copper plate $\frac{1}{16}$ " thick with a circular hole of .08 inch diameter, and spaced $\frac{3}{2}$ " apart, the lim-

iting rate of rise of voltage was found to be 2×10^6 volts per second per grid.

With the same thickness of plate, and spacing between grids, but with .04 inch holes, the limiting rate of rise of voltage was found to be 3.7×10^6 volts per second per grid, showing the great advantage of the smaller hole.

With similar grids $\frac{1}{16}$ inch thick, spaced $\frac{3}{2}$ inch apart, with a hole diameter of .081 inches, the limiting rate of rise of voltage was found to be 3.4×10^6 volts per second per grid, while for grids $\frac{3}{2}$ inch thick, spaced $\frac{3}{2}$ inch apart, with a .081 inch diameter round hole, the limiting rate of voltage rise was found to be 6×10^6 volts per second per grid. This shows the advantages of thicker grids.

The figures given above indicate that the grid spacing and the width of the grid openings should be made as small as is consistent with the mechanical requirements of the design, and the danger of melting by separate arcs.

I have obtained very good results with grids spaced $\frac{1}{2}$ of an inch from each other. A further decrease of the grid spacing introduces difficulties on account of the natural warping of the material of the grids, causing the same to contact with each other, and on account of the mechanical problem of providing a suitable insulating medium of the required thickness.

As stated before, a decrease in the size of the grid openings tends to split the arc into separate short arcs. With a speed of arc motion such as is obtainable in an arc chute of moderate length, the arc terminals on the grids will melt the same and decrease the de-ionizing action. It has been found that this action of the grids takes place when the arcing voltage becomes greater than about 25 volts per grid. I have further found that it requires a much stronger magnetic field, or force, to move the arc into the grids without melting when the size of the grid openings is reduced.

It is, of course, desirable, for the successful accomplishment of the de-ionizing action, that the rise in voltage across the arc terminals when the current becomes zero, shall be uniformly divided between the grids interposed between the arc terminals, in order to prevent an excessive voltage across any pair of grids. In high-voltage applications, where the number of grids in series is relatively large, it may happen that, on account of the capacity of the grids to the ground, and on account of the difference in the charges acquired during the arcing preceding the current zero, the voltage may not be uniformly divided among the grids, so that some of the same become overstressed and cause restriking of the arc.

In order to positively secure uniform voltage distribution over all of the grids in the de-ionizing chamber, I may provide a high-

130

impedance balancing resistor shunting the several grids. Thus, as shown in Fig. 11, a single-break arcing chamber may have a plurality of grids 105 mounted between arcing electrodes 106 and 107. The individual grids have terminal connections 108 extending outside the arcing chamber, and a high resistance 109 is connected in shunt to the several grids. The impedance of the shunt resistor 109 is so high that the current therethrough is substantially negligible, the principal function of the resistor being to maintain a uniform voltage gradient between the grids.

As stated before, the relation between the thickness of the grid and the size of the grid hole affects the operation of the circuit breaker in two ways. In the first place, up to a certain point, for a given size of grid opening, the thicker the grid wire, the higher is the permissible rate of voltage rise without re-ignition. On the other hand, an increase in the thickness of the grids raises the arcing voltage per grid for the period before the arc extinction, causing arc splitting and excessive heating of the grids, with a resulting decrease in the de-ionizing action.

The amount of current flowing directly to the metal of the grids in an arc is a function of the arc voltage per grid and is negligible for less than 20 volts per grid. However, an increase in the arc voltage per grid above 30 volts usually causes the grid current to become excessive and the grids begin to function as arc electrodes, causing melting of the grids.

As shown in Fig. 12, I may combine the advantages of the thick grids with respect to the permissible high rate of voltage rise, with the advantages of thin grids with respect to low arc voltages per grid, by connecting thin wire grids together, in pairs, by resistors 110. When the arc is playing, there is no appreciable current in the resistors 110 between the grids of each pair, the grid openings being large enough to permit free play of the arc shunting said resistors. When the arcing current reaches zero, the grids making up a pair take on the same potential, on account of the resistor connections between the same, and de-ionize the arc space like a thick grid.

The speed with which the de-ionizing action takes place in a given de-ionizing structure depends upon the speed with which the positive ions move through the space of the arc under the action of the electric field. The speed which the ions acquire under the action of a field of unit strength is a measure of the mobility of the ions, and varies in gases inversely with the molecular weight. Thus, the positive ion in hydrogen will move seven or eight times as fast as the positive ion in air. Hence, if a de-ionizing chamber is enclosed in an atmosphere of hydrogen, the opening in the grids may be made seven

times as large as they would have to be in air in order to give the same rate of de-ionization.

In Fig. 13 is shown a modification of my invention, wherein a de-ionizing structure 111 is enclosed in a chamber 112 which is filled with hydrogen supplied through openings 113 from a hydrogen generator or tank 114. The de-ionizing structure comprises two arcing terminals 119 and a bank of grids 120 disposed therebetween. The arc is started by the operation of a suitable operating mechanism 121 to interrupt the connection between the arcing terminals 119 of the circuit.

The rate of de-ionization of the arc space may also be increased by reducing the pressure of the gaseous medium in which the arc is drawn, as shown diagrammatically in Fig. 14, wherein a de-ionizing structure 122, such as that shown in Fig. 13, is enclosed in a chamber 123 which is maintained under reduced pressure by means of a vacuum pump 124. Since the velocity of the ions, acquired under the action of a given electric field, increases with a decrease in the pressure, the de-ionizing action is greatly improved when operating under such conditions. Thus, if the pressure is reduced to $\frac{1}{10}$ of the atmospheric pressure, grids having openings 0.5 inches wide will give the same rate of de-ionization as grids having openings 0.05 inches wide at atmospheric pressure.

In order to obtain the full de-ionizing effect of the grid structures, it is, of course, important that the arc drawn between the arcing contacts, be moved into the grids before the current passes through the next zero. It requires a relatively strong force to move the arc into the grid structure. Accordingly, the magnetic blow-out mechanism, as shown in Figs. 1 to 3, inclusive, must produce a strong magnetic field across the space where the arc is drawn, in order to prevent the arc from hanging at the entrance edges of the grids and melting the same. However, once the arc is in the grid structure, it is undesirable to move the arc very fast, as it is difficult to keep all parts of the arc at the same speed and the arc tends to break up into separate arcs. The blow-out magnet shown in Figs. 1 to 3, inclusive, is so designed as to reduce the density of the magnetic field in the upper portion of the arc chute, the pole shoes 55 terminating about the middle of the arc chute, and the upper half of the pole-shoe plates 56 being of reduced thickness to decrease the density of the field.

In Fig. 15 is shown a single arc-chamber de-ionizing structure 150 wherein the magnetic field in the interior of the grid structure is still further reduced, by providing the pole-shoe plates 151 disposed on each side of the grids with large perforations 152 greatly increasing the reluctance of this part of the

magnetic circuit with a resulting decrease in the field strength.

Fig. 16 shows an arc chute similar to that in Fig. 15, wherein the magnetic field inside the grid structure is still further decreased by providing non-magnetic, highly conducting plates 161 on both sides of the grid structure adjacent to the pole shoe plates 162. Such construction secures a rapid falling off of the magnetic field as the arc enters the grid structure, since the eddy currents in the highly conducting, non-magnetic plates 161 exercise a shielding effect, preventing the flux induced by the pole shoes 162 from entering into the upper portion of the de-ionizing structure.

It may be desirable to positively prevent the arc from moving upwardly, outside of the grids. To this end, a blow-out magnet 163 may be mounted on both sides of the upper portion of the grid structure 164 of the de-ionizing chamber. The blow-out magnet 163 is suitably excited to exercise a downwardly directed force upon the arc.

Fig. 17 shows another advantageous construction which secures the desired decrease of the magnetic field in the grid structure. The pole shoes 171 are staggered, and the field induced thereby has a tendency to drive the arc towards one side of the free path 173 in the grids of the arc chute. Such arc motion promotes the continuity of the arc and opposes the splitting of the same. The highly conducting, non-magnetic plates 174 extend above the pole shoes 171 to prevent the flux induced by the pole shoes from entering the grid structure. The arc moves in the arc chute principally by reason of the convection currents of the surrounding gas, as in the case of the well-known arc horn utilized in lightning arresters.

Referring again to Fig. 1, it is noted that when the arc is moving into the grid structure, a layer of hot ionized gases usually adheres to the insulating walls 52 on both sides of the arcing horns 41 and 42. Since the conducting plates or horns 41 and 42 in this space are very far apart, the de-ionization of this layer of hot gas may proceed very slowly and cause re-ignition, after the voltage begins to rise in the next alternation.

In order to overcome this difficulty, in the modification shown in Fig. 17, the insulating walls 178 closing the sides of the horn-like arcing chamber 179 may be lined with a plurality of juxtaposed insulated metallic bodies constituting miniature de-ionizing grids on both sides of the horn-like arcing chamber. Thus, in Fig. 17, the ends of the individual grid sheets 177 abut against the insulating walls 178 on both sides of the horn-like arcing chamber 179. The individual grids are, of course, insulated from each other by means of mica spacers 180.

Fig. 18 shows a de-ionizing chamber

wherein the arc is moved into the arc chute 181 by means of an air blast. The arc is drawn between two horn-like electrodes 182 by means of an arcing contact arm 183. An air nozzle 184, which is supplied with air from a high-pressure source by means of a hose 185, directs a blast of air upon the arc which is drawn between the arcing electrodes 182. On account of the relatively narrow passage for the air at the lower portion of the arcing electrodes 182, the velocity of the air is very great, causing a rapid movement of the arc into the grid structure, as is required for satisfactory operation. The opening in the arc chute 181, however, is much larger than the opening at the lower portion of the arcing horn 182. The velocity of the air blast is, accordingly, greatly decreased and the motion of the arc is slowed down to a value required for the satisfactory operation of the circuit breaker.

In order to de-ionize the layer of gas near the insulating walls (not shown) on both sides of the horn-like arcing plates 182, the grids 186 of the de-ionizing chamber have extensions 187 projecting downwardly near the insulating walls leaving a free space in the middle for the motion of the arcing-contact arm 183.

The difficulties resulting from drawing the arc between the electrodes outside the grid structure, and subsequently blowing the same into the grid structure, may be avoided by drawing the arc through the openings in the grid structure itself. Such construction is shown in Fig. 19, wherein the grids 191 in the arc chute 192 are provided with a longitudinal perforation 193 through which the arcing contact member 194 is moved by means of an arcing contact arm 195, similar to the arcing contact arm 15 in Fig. 1. The arcing contact member 194, which draws the arc, is preferably of rectangular cross-section, of narrow width and relatively great height so that the perforation in the grids is of such width as to secure the de-ionization of the arc space in case that small-current arcs remain playing in the perforation 193 without moving into the grids.

Another construction for positively securing the drawing of the arc within the grid structure is shown in Fig. 20, wherein the movable arcing electrode 201 makes a wiping contact with the grids 202 at the bottom of the de-ionizing chamber 203. One end of the arcing contact member 201 is covered with a block of insulating material 204 which is so aligned with the surface of the arcing contact member 201 as to slide beneath the grids, behind the conducting surface of the contact member. The arc is drawn by the moving contact member 201, and is forced into the grid structure by the insulating member 204.

In the foregoing explanation, grid structures made of wire gauze have been described. It is, of course, clear that any other structure may be utilized which sub-divides the space between the arcing electrodes into a large number of small spaces, all of the spaces being provided with conducting centers or nuclei for exercising a de-ionizing action throughout the entire space between the arcing electrodes.

In Figs. 21 and 22, the grids are shown in the form of metallic sheets 210 having perforations 211, providing a free path for the play of the arc between the arcing electrodes 212. In the particular type of grids shown in this figure, the perforations are so formed as to provide a double comb, facing a rectangular, narrow arcing-switch blade 213 on both sides thereof. The grid sheets are made of resilient material, such as phosphor bronze. The spacing between the ends of the comb teeth 214 is smaller than the width of the switch blade 213 so that, when the same is in its closed position, shown in the drawings, the teeth of the de-ionizing combs are bent outwardly, ready to spring back and form a narrow slot immediately upon withdrawal of the switch blade. Such construction assures a positive de-ionizing action upon the opening of the circuit breaker, since the arc drawn by the switch blade 213 in the space between the teeth 214 of the grids 210 is enveloped, in every portion thereof, by a conducting de-ionizing member which will secure rapid restoration of the arcing space to its original non-conducting condition, without the necessity of further arc movement.

To operate the circuit breaker just described, the right-hand portion 215 of the comb-like grid structure may be withdrawn somewhat to the right so as to provide a sufficiently large opening for inserting the switch-blade 213. The comb-structure is subsequently moved back into the normal operating position in which the comb teeth of the grids are bent by the switch-blade, as shown in the drawings. The circuit breaker may also be so constructed that the switch blade is inserted into the comb-like structure from one side and removed therefrom through the other side, as indicated by the arrow 216 in Fig. 22. An additional grid structure 217 may be placed above the comb-like structure for receiving the arc drawn between the comb-like grids, in case the arc moves upwardly.

In Figs. 23 and 24 is shown a de-ionizing chamber which secures the effect of the comb-like arrangement shown in Figs. 21 and 22, with a construction utilizing wire-gauze grids. The de-ionizing chamber is divided into a lower portion 231 and an upper portion 232 pressing on both sides of an arcing switch blade 233, the grids being of resilient material

and the slots for the switch blade being somewhat narrower than the width of the switch, so as to cause the ends of the grids facing the switch-blade to spring back after the blade has been withdrawn from the grid structure, in the direction shown by the arrow 234.

A very simple mechanism for avoiding the danger of re-ignition by reason of failure of the arc to move into the de-ionizing grid structure, is shown in Fig. 25. One of the arcing electrodes is shown in the form of a conducting vessel 251 containing mercury 252, the other electrode being in the form of a metallic plate 253 which is downwardly movable until it contacts with the mercury. The metallic plate 253 carries an insulating housing 254 in which is mounted a bank of horizontally disposed grids 255. The grids 255 are located beneath the movable electrode 253 and are entirely immersed when the movable electrode is in contact with the mercury. When the electrode 253 is raised to its open position, illustrated in the drawings, the arc is drawn between the electrode surface and the mercury and is confined to the space occupied by the grids 255, thus positively insuring a prompt de-ionizing action.

Another mechanism for drawing the arc through the de-ionizing grids by means of mercury is shown in Fig. 26, wherein a vessel 260, of insulating material, is pivotally mounted to move from the horizontal position shown in the drawings to a vertical position. The vessel 260 has two enlarged compartments 261 and 262, at the ends thereof, and the space between the two compartments is filled with a bank of grids 263 of a construction similar to that described in connection with the other de-ionizing structures. Electrodes 264 and 265 extend into the compartments 261 and 262, respectively, the two electrodes constituting arc terminals of the circuit breaker. The vessel 260 contains a body of mercury 266 which fills the lower portion thereof, providing a connection between the two electrodes 264 and 265. By turning the vessel 260 to the vertical position, the mercury breaks contact with the electrode 264 which is moved upwardly, and the receding mercury draws an arc through the grids, wherein the arc is subsequently de-ionized.

In the design of the de-ionizing chamber, care must be taken to avoid injury to the grid sheets by the arc drawn between the main arcing plates. To this end, it is desirable to secure a movement of the arc within the arc chute, in order to prevent the arc from remaining stationary and playing through one particular portion of the grid structure. I have found, however, that the vapor blast emanating from the arc terminals on the plates on both sides of the grid structure may, under circumstances, exercise a detrimental effect upon the grids.

The heating of the de-ionizing grids in the arc chute takes place in two ways, first, by radiation and thermal conduction from the hot gases of the arc and second, by the direct evolution of heat at the surface of the grid material by the currents flowing into the grids. It has been found that, when a wire is placed in an arc near an arc terminal and a potential is applied to it, considerable current flows to the wire. If the wire is moved further from the arc terminal, the current to the wire becomes negligible. Thus, in the case of a 50-ampere arc, a wire placed one-sixteenth of an inch from either electrode and maintained 30 volts negative with respect to the arc carried a large current, while the same wire placed one-half inch from the arc terminal and maintained 140 volts negative with respect to the arc carried only a very small current.

I believe that the change in the amount of current flowing to the wire, dependent upon the spacing of the same from the arc terminal, is due to the fact that the arc electrodes give off considerable quantities of metal vapor. Such vapor has a much lower ionizing potential than air and is, therefore, thermally ionized at a much lower temperature than air. Accordingly, when a wire is spaced close to one of the arc electrodes, it becomes surrounded by metal vapor and a relatively low potential will suffice to produce a large current to the wire. However, when the wire is farther away from the electrode, it is surrounded by air and the current thereto will be negligible, even if the potential applied is relatively high.

In Fig. 27, I have shown a de-ionizing chamber wherein the grid sheets 270 are protected from the effect of the vapor blast 271 emanating from the arc terminals 272, upon the electrodes, by bending the terminal plates 273, away from the grid structure and shaping them like horns. As the arc 271 is moved upwardly in the grid structure, the arc terminals move outwardly upon the terminal plates 273 and the blast 271 is directed away from the grids instead of into the grids, as in the case where the terminal plates are parallel to the grid sheets.

Many other constructions may be employed to protect the grid sheets from the direct action of the vapor blast emanating from the arc electrodes.

Thus, in Fig. 28, the arcing chamber 280, similar to that of Fig. 11, is provided with insulating barriers 281 breaking up the direct path between the terminal plates 282 and the de-ionizing grid sheets 283, the arcing between the two terminal plates 282 taking place through a somewhat tortuous path through staggered openings 284 in the insulating barriers.

In Fig. 29 is shown another modification of my invention wherein the grid sheets 290 are

held between insulating plates 291 which are provided, in the middle thereof, with openings 292 for the arc. The terminal plates 293, between which the arc drawn by the interrupting terminals is blown, are placed outside of the insulating plates 291 and are so disposed that the arc blast 294 emanating from the arc terminals is directed away from the arc openings 292 in the insulating plates 291 on both sides of the grids.

Fig. 30 is a single view embodying adjunctive features of the figures heretofore described. In this figure the various reference numerals designate the same parts as in the preceding description so that the structure illustrated in Fig. 30 should be clear without separate enumeration of its component elements.

There has been described a variety of structures and has been set forth the principles whereby it is possible to open circuits carrying very heavy currents at high voltages without the employment of oil for quenching the arc drawn between the circuit-interrupting terminals. I have pointed out that, in alternating-current circuit breakers, arc re-ignition may be successfully prevented by artificially increasing the rate of de-ionization of the arc space, and so controlling the rate of voltage rise across the arc terminals that the potential gradient in the de-ionized spaces never reaches a value at which re-ignition will occur.

My invention may be embodied in numerous other structures, and the features of the artificial increase of the rate of de-ionization may be embodied in other types of circuit breakers and in other devices wherein it is important to prevent arc re-ignition. I desire, therefore, that the language of the appended claims be construed broadly to cover all modifications and arrangements falling within the spirit of my invention.

I claim as my invention:

1. A circuit breaker comprising a pair of, 110 separable arcing contact members, a de-ionizing chamber for the arc drawn between said contact members, said chamber comprising de-ionizing conducting elements subdividing the arc space into small spaces less than $\frac{1}{8}$ inch, said conducting elements being so supported that the latter conduct substantially no arc current.

2. The combination with an alternating-current circuit, of a circuit breaker having a de-ionizing chamber comprising parallel arc terminal members and conducting nuclei subdividing the arc space between said terminal members into small spaces associated with said nuclei, means for drawing an arc and transferring the ends of said arc to said parallel arc-terminal members, and means for limiting the rate of voltage rise between said terminal members.

3. The combination with a circuit breaker,

of a de-ionizing chamber comprising parallel arc terminal members and conducting members subdividing the arc space between said terminal members into small spaces associated with said members, and means for drawing an arc and transferring the ends of said arc to said parallel arc-terminal members, said chamber containing a gas of low molecular weight.

4. A circuit breaker comprising a pair of current-carrying terminals and a pair of circuit-interrupting terminals, an arc de-ionizing chamber associated with said circuit-interrupting terminals comprising arc terminal members and a mass of conductors subdividing the space between said arc terminal members into small spaces, said chamber containing a gaseous medium at reduced pressure.

5. A circuit breaker comprising a pair of current-carrying terminals and a pair of circuit-interrupting terminals, an arc de-ionizing chamber associated with said circuit-interrupting terminals comprising arc terminal members uniformly spaced from each other throughout their area and electrically connected in said circuit and a mass of conductors subdividing the space between said arc terminal members into a series of small spaces permitting arc play.

6. A circuit breaker comprising a pair of terminals for closing and opening a circuit, and de-ionizing means for the arc developing upon opening said circuit breaker, said de-ionizing means comprising a plurality of perforated conducting sheets superposed upon each other and disposed transversely across the arc space, said sheets being insulatingly spaced from each other and arranged to permit a continuous arc movement therein.

7. In an alternating-current circuit breaker having a pair of arcing terminals, means for opening the circuit by drawing an arc between said terminals, and de-ionizing means for said arc, said de-ionizing means comprising a plurality of superposed conducting sheets disposed transversely across the arc length, insulating spacers between said sheets, and means for maintaining a predetermined potential balance between said sheets.

8. In an alternating-current circuit breaker, a pair of terminals for drawing an arc to open the circuit, arc terminal members for said arc comprising parallel plates on which the ends of the arc may be moved, a plurality of de-ionizing sheets disposed across the arc path between said terminal members, and impedance means shunting said path to limit the rate of voltage rise between said terminal members.

9. The combination with an alternating-current circuit, of a circuit-breaker comprising a pair of main current-carrying contact members and auxiliary arcing contact members for drawing an arc to open the circuit,

means including terminal members parallel to said main contact members for dividing said arc into a plurality of sections, and de-ionizing sheets disposed across the arc path in each section between said terminal members.

10. In an alternating-current circuit breaker, the combination of a pair of main circuit-closing contact members, means for interrupting the circuit by drawing a plurality of arcs providing a by-pass path around said contact members, and means for successively extinguishing said arc and reducing the arc current in the several arcs in successive half cycles comprising impedance means connected in parallel to some of said arcs to prevent re-ignition thereof and in series with other of said arcs to reduce the residual arc current in the following half cycle.

11. An alternating-current circuit breaker comprising a pair of main current-carrying terminals and means for drawing a series of arcs in parallel to said main terminals to interrupt the circuit, an impedance shunting the first arc and being of such value as to limit the rate of voltage rise across the terminals of said first arc to a value at which the arc will not re-ignite after the first current node, the arc in the following alternation after the extinction of said first arc being limited to the residual current flowing through said impedance.

12. In an alternating-current circuit breaker, the combination of a pair of main contact members, means for interrupting the circuit by drawing a plurality of arcs providing a by-pass path around said contact members, and means for successively reducing the arc current in successive half cycles comprising de-ionizing conductors subdividing the arc spaces into a relatively large number of small spaces with a de-ionizing nuclei in each space, and impedance means of different values connected in parallel to said arcs to limit the rate of voltage rise between the de-ionizing conductors disposed at different points of the arc-space length.

13. In an alternating-current circuit breaker having a pair of uniformly spaced arc terminal members, means for drawing an arc and causing said arc to play between said arc terminal members, and arc re-ignition preventing means comprising superposed de-ionizing sheets longitudinally subdividing the arc space into a relatively large number of small spaces with de-ionizing nuclei in each space, and impedance means shunting the arcing terminals to control the rate of voltage rise across the arc terminals, the distribution of the de-ionizing nuclei and the rate of voltage rise being correlated to prevent the voltage gradient in the de-ionized spaces of the arc from reaching a value at which ionization occurs.

14. The combination with an alternating-

- current power circuit, of a circuit breaker having a pair of uniformly spaced arc terminal members electrically connected in said circuit, means for opening the circuit by 5 causing an arc between said terminal members, means for moving the ends of said arc on said arc terminal members, and arc re-ignition preventing means comprising conducting de-ionizing centers distributed over 10 the arc space between said terminal members, the spacing between said centers being so chosen with respect to the constants of the circuit resulting when the arc current is zero that the space between said electrodes be- 15 comes de-ionized at such rate that the voltage gradient in the de-ionized spaces does not reach a value at which it causes ionization-by-collision.
15. The combination with an alternating- 20 current power circuit, of a circuit breaker comprising separable arcing contact members, an arc chamber adjacent to said contact members, said arm chamber comprising a pair of uniformly spaced arc-terminal mem- 25 bers to which the ends of the arc are transferred from said arcing contact members, a plurality of conducting sheets spaced from each other and disposed transversely to the path between said terminal members, means 30 for causing said arc to travel into said sheets and for causing the ends of said arc to move on said arc-terminal members, and means for causing the rate of voltage rise across the arc- 35 ing terminals, subsequently to arc-current zero, to be of the order of 10^7 volts per second per sheet.
16. A circuit breaker comprising separable 40 arcing contact members, an arc chamber adjacent to said contact members, said arc chamber comprising a pair of uniformly spaced arc-terminal members, a plurality of conducting sheets spaced from each other and disposed transversely to the path be- 45 tween said terminal members, means for causing said arc to travel into said sheets and for causing the ends of said arc to move on said arc-terminal members and to continue to travel therein during the full duration there- 50 of, and means for confining the arc travel to the space occupied by said sheets.
17. An alternating-current circuit breaker comprising separable arcing contact members, an arc chamber adjacent to said contact members, said arc chamber comprising a 55 pair of spaced arc-terminal members, a plurality of perforated conducting sheets spaced from each other and disposed trans- versely to the path between said terminal members, means for causing said arc to travel 60 into said sheets, insulating walls on both sides of the space of arc travel, and conducting de-ionizing nuclei in the spaces near the insulating walls adjacent to the arcing space between said contact members.
- 65 18. In an alternating-current circuit breaker, a current interrupting unit, comprising a stack of superposed conducting de-ionizing sheets separated from each other by small air spaces, said sheets having perforations providing an arcing path through 70 said stack, an arcing contact member for opening said circuit, said contact member being movable to draw an arc through said perforations, the width of said perforations being so small that upon the occurrence of a current node, the arc space is de-ionized at such rate that the potential gradient in the de-ionized spaces does not reach a value at which re-ignition occurs.
19. The combination with an alternating- 75 current circuit, of a circuit breaker comprising a pair of arcing contact members, means for establishing an arc in a gaseous medium between said contact members for interrupt- 80 ing the circuit, a pair of electrode plates hav- 85 ing uniform spaces therebetween and extending in spaced relation laterally of said arc, a plurality of spaced conducting sheets interposed between the said plates and extending into proximity to said arc, and means operative in an interval of time that is short as compared to the half-period of the alter- 90 nating-current circuit for causing the arc to move laterally into the space traversed by said sheets and for moving the ends of said arc on said electrode plates, said sheets and the lateral arc movement therewithin being of such size and speed, respectively, that the arc remains within the space trav- 95 ersed by the sheets until it is extinguished substantially without melting or pitting said sheets.
20. The combination with an alternating 100 current circuit, of a circuit breaker comprising a pair of arc terminals, means for es- tablishing an arc in a gaseous medium be- 105 tween said terminals for interrupting the circuit, a pair of electrode plates extending in spaced relation laterally of said arc, a 110 plurality of spaced conducting reticulated sheets interposed between the said plates and extending into proximity to said arc, and means operative in a time short as compared to the half-period of the alternating-cur- 115 rent circuit for causing the arc to move laterally into the space traversed by said sheets, said sheets and the lateral arc move- 120 ment therewithin being of such size and speed, respectively, that the arc remains within the space traversed by the sheets until it is extinguished substantially without melting or pitting said sheets.
21. The combination with an alternating- 125 current circuit, of a circuit breaker comprising a plurality of pairs of serially connected 130 arc terminals in a gaseous medium, and means including a plurality of spaced con- ducting solid bodies disposed in the spaces traversed by the several arcs for hastening 135 the de-ionization of the gas in said spaces 140

immediately following the passage of the alternating current through zero value.

22. An alternating-current circuit breaker comprising separable arcing contact members, an arc chamber adjacent to said contact members, said arc chamber comprising a pair of uniformly spaced arc-terminal members, a plurality of conducting sheets disposed transversely to the path between 5 said terminal members, said sheets being insulatingly spaced from each other by distances less than $\frac{1}{8}$ inch, and means for securing a speed of arc travel on said sheets and arc-terminal members at which the local 10 heating of the sheets and arc-terminal members will not cause melting of the same.
23. An alternating-current circuit breaker comprising separable arcing contact members, an arc chamber adjacent to said contact members, said arc chamber comprising a pair of spaced parallel arc-terminal members connected in parallel with said arcing contact members, a plurality of conducting sheets disposed transversely to the path 15 between said terminal members, said sheets being insulatingly spaced from each other by distances less than $\frac{1}{8}$ of an inch, means for securing continuous arc motion within said sheets and on said arc-terminal members 20 during the entire duration thereof, and means whereby, upon arc extinction the rate of voltage rise between adjacent sheets is of the order of 10^7 volts per second per sheet.

24. In an alternating-current circuit breaker, a pair of separable arcing contact members, a de-ionizing chamber for the arc drawn between said contact members, said chamber comprising conducting grid sheets insulatingly spaced from each other, said 30 sheets being disposed transversely to the arc path, said grid sheets having perforations of sufficient size and number to permit arc play therethrough without breaking up into separate arcs.

45. 25. In an alternating-current circuit breaker, a pair of separable arcing contact members, a de-ionizing chamber for the arc drawn between said contact members, said chamber comprising conducting grid sheets insulatingly spaced from each other, said 50 sheets being disposed transversely to the arc path, said grid sheets having perforations of sufficient size and number to permit arc play therethrough without splitting the arc, the 55 spacing between adjacent grid sheets being of the order of $\frac{1}{8}$ inch.

26. The combination with an alternating-current circuit having a source of energy, of a circuit breaker, comprising a pair of arcing 60 contact members separable to open said circuit, a de-ionizing structure for the arc incident to the separation of said contact members, said de-ionizing structure comprising a plurality of conducting grids superposed 65 upon each other across the arc space and

dividing the same into a multitude of de-ionizing centers which are relatively ineffective during the continuance of the arc, the mass of the conducting material of said grids being so distributed throughout the arc space that, upon the occurrence of a current node, said space is so de-ionized that the potential gradient in the de-ionized spaces never reaches a value at which re-ignition occurs.

27. A circuit breaker comprising a pair of terminals for closing and opening a circuit, and de-ionizing means for the arc developing upon opening said circuit breaker, said de-ionizing means comprising a plurality of perforated conducting sheets superposed upon each other and disposed transversely across the arc space, one dimension of the perforation being less than one-tenth of an inch, said sheets being insulatingly spaced from each other and arranged to permit a continuous arc movement therein.

28. A circuit breaker comprising separable arcing contact members, an arc chamber adjacent to said contact members, said arc chamber comprising a pair of spaced arc-terminal members on which the arc may be moved without increasing its length, a plurality of conducting sheets spaced from each other and disposed transversely to the path between said terminal members, means for causing said arc to travel into said sheets and to remain therein during the full duration thereof, and for causing the ends of the arc to travel on said arc-terminal members.

29. The combination with an alternating-current circuit, of a circuit-breaker comprising a pair of main current-carrying contact members, auxiliary arcing contact members for drawing an arc to open the circuit and a pair of arc-terminal members on which the arc may be moved without increasing its length electrically connected in said circuit and deionizing sheets disposed across the arc path between said terminal members.

30. In a circuit interrupter, a pair of diverging arc horns, a pair of uniformly spaced arc-terminal members extending from said arc horns, a plurality of closely spaced members of conducting material between said arc-terminal members for deionizing an arc, means for drawing an arc and transferring said arc to said pair of arc horns, and means for moving said arc on said arc horns and arc-terminal members.

In testimony whereof, I have hereunto subscribed my name this 27th day of August, 1925.

JOSEPH SLEPIAN.
